Graham & Lainie
ATTORNEYS.

UNITED STATES PATENT OFFICE

JOHN A. ZUBLIN, OF LOS ANGELES, CALIFORNIA.

PUMP.

Application filed December 11, 1923. Serial No. 679,977.

To all whom it may concern:

Be it known that I, JOHN A. ZUBLIN, a citizen of the Republic of Switzerland, residing at Los Angeles, in the county of Los Angeles, State of California, have invented a new and useful Pump, of which the following is a specification.

My invention is particularly applicable to pumps which are applied to the pumping of fluids containing abrasive material, such as water or oil containing silt or sand. Such conditions are ordinarily found in pumps applied to oil and water wells and for many other applications. Under such conditions the wear upon the plunger and the pump barrel of the usual form of pump is considerable. I have found, however, that if the plunger be provided with a sharp upper edge and this edge be maintained at intimate contact with the pump barrel walls, it is possible to prevent the entry of the abrasive material into the space between the plunger and the wall of the pump barrel, and thus greatly reduce the cutting action on the plunger and pump barrel. I have found further that it is possible by a suitable design of pump to make an edge which is not only extremely sharp initially but which maintains itself in this condition over long periods of use. This is accomplished by subjecting this edge to swaging action through the operation of the pump, as will hereinafter be explained.

Further objects and advantages will be made evident hereinafter.

Referring to the drawings which are for illustrative purposes only,

Fig. 1 is a section through the barrel and plunger of an oil well pump embodying my invention.

Fig. 2 is a similar section through an alternate form of my invention.

Fig. 3 is a plan view of the plunger used in the form shown in Fig. 2.

Fig. 4 is a section through the pump rod on a plane represented by the line 4-4 of Fig. 2, the plunger and barrel being omitted for the sake of clearness.

In the form of the invention shown in Fig. 1, a hollow plunger 11 is fitted inside a pump barrel 12, being reciprocated by a pump rod 13 having a conical seat 14 on which the plunger 11 seats on the up stroke. Secured on the pump rod 13 is a cage 15 having openings 16 therethrough and having a ring 17 on the lower end thereof. The

upper end of the plunger 11 is preferably conoidal and the lower end of the member 17 is of such a shape as to fit therein. On the up stroke the plunger 11 rests upon the seat 14 but as the pump rod 13 starts upon the down stroke, the plunger 11 is frictionally retarded in the barrel 12 and remains stationary until it is struck by the member 17, the plunger 11 being thereafter forced downwardly by the cage 15. At the beginning, therefore, of each down stroke the plunger 11 is struck a light blow by the portion 17 of the cage 15, the conoidal lower surface of the member 17 being forced inside the co-acting surface of the plunger 11, thus tending to spread or expand the plunger 11 and to maintain a sharp knife edge having the form shown at 20 in Fig. 1. This sharp edge fits tightly inside the barrel 12 and tends to scrape from the walls of the barrel any adhering mud or other abrasive material which is thereon, thus preventing the abrasive from entering the space between the plunger 11 and the barrel 12.

In the form of the invention shown in Fig. 2 I provide a pump barrel 50 having a plunger 51. A pump rod 52 extends downwardly and is provided with a seat 53 at the lower end thereof and a cage 54 at the top thereof. The seat 53 is a freely sliding fit inside the barrel and is provided with saw cuts 55 which extend vertically therethrough around the edges thereof and provide channels through which the fluid may flow on the down stroke of the pump. The lower end of the plunger 51 is conoidal in form and it is subjected to the same swaging action as the edge 20 mentioned in connection with Fig. 1. In other words, on the down stroke the plunger 51 is in its upper position resting against the member 54 and it remains in this position until it reaches the bottom of its stroke and the pump rod 52 starts upwardly. At the start of the up stroke of the pump rod 52 the plunger 51 is stationary and is therefore struck a sharp blow by the seat 53, this blow tending to swage out the lower edge of the plunger and make it fit tightly inside the barrel 50.

It is not absolutely necessary that the edges of the plunger should be conoidal and the arrangement shown in the upper portion of Fig. 2 is fairly efficient. In this form the lower portion of the cage 54 strikes against the upper end of the plunger 50,

tending to swage it outwardly and make it fit tightly against the inner walls of the barrel 50.

I claim as my invention:

- 5 1. In a pump, the combination of: a pump barrel; a hollow piston fitting in said pump barrel; a pump rod; and means on said pump rod for operating said piston, said means being so arranged as to batter out a 10 thin edge of said piston against the pump barrel.
- 15 2. In a pump, the combination of: a pump barrel; a hollow piston fitting in said pump barrel and having a sharp edge at one end thereof in contact with the inner surface of said pump barrel; a pump rod; and means on said pump rod for swaging said plunger against said barrel.
- 20 3. In a pump, the combination of: a pump barrel; a piston fitting in said barrel, said piston having a sharp edge at its point of contact with said barrel; and means for swaging said edge by the operation of said pump to maintain it in intimate contact 25 with said barrel.

4. In a pump, the combination of: a pump barrel; a piston fitting in said barrel and having a sharp edge in intimate contact with said barrel; a pump rod; means for attaching said pump rod to said plunger in such a manner that there is a slight lost motion between said pump rod and said plunger; and means for utilizing said lost motion to swage said sharp edge against the inner surface of said barrel. 30 35

5. In a pump, the combination of: a pump barrel; a piston fitting in said barrel and having a sharp edge in intimate contact with said barrel; a pump rod; means for attaching said pump rod to said plunger in such a manner that there is a slight lost motion between said pump rod and said plunger; and means carried by said pump rod for striking a sharp blow on said plunger closely adjacent the wall of the barrel at the beginning of each stroke of the pump. 40 45

In testimony whereof, I have hereunto set my hand at Los Angeles, California, this 4th day of December, 1923.

JOHN A. ZUBLIN.
